UNITED STATES PATENT OFFICE.

ELMO L. BROWN, OF ASHEVILLE, NORTH CAROLINA.

FLOWER-STEM-REENFORCING MACHINE.

Application filed February 13, 1925. Serial No. 8,919.

To all whom it may concern:

Be it known that I, ELMO L. BROWN, a citizen of the United States, residing at Asheville, in the county of Buncombe and State of North Carolina, have invented certain new and useful Improvements in a Flower-Stem-Reenforcing Machine, of which the following is a specification.

This invention relates to flower stem reenforcing machines and has more particular reference to a machine whereby reenforcing sticks may be applied alongside of the stems of flowers after which thin wire is automatically wrapped therearound for securing the stick to the stem for obviously reenforcing the same.

It has heretofore been necessary to perform this operation by hand and the same is very tedious and complicated and requires the services of a skilled artisan.

Through the provision of a machine of this character natural flowers may be reenforced at their stems by an unskilled person, and in a highly simple and expeditious manner.

An additional object of the invention is to provide automatic means for moving the sticks into position alongside the flower stem during the time that the wire wrapping elements are being returned to their normal positions in order that the stick will be properly positioned at the time of inserting a flower stem for obviously preventing loss of time in the operation of the machine.

A further and important object is to provide automatic means for severing the wire that is brought from a source of supply after the wrapping operation has been completed.

A further and important object is to provide a machine wherein the elements of construction may be so arranged as to permit a wire carrying spool that constitutes an essential element of the invention, to be replenished from a wire reel that is mounted for rotation within the machine.

A still further object is the provision of a flower stem reenforcing machine that is of relatively simple construction and highly efficient in operation, and of such a nature as to permit the ready disassembling of the same for repair or renewal purposes.

A final salient object is the provision of a machine of this character that may be readily actuated by hand power or motor as desirable.

With the foregoing and other objects in view as the nature of the invention will be better understood, the same comprises the novel form, combination and arrangement of parts hereinafter more fully described, shown in the accompanying drawings and claimed.

In the drawings wherein like reference characters indicate corresponding parts throughout the different views:

Figure 1 is a front elevational view of the machine, the casing door thereof being in open position.

Figure 2 is a detailed vertical sectional view taken substantially upon the broken line 2—2 of Figure 1 for disclosing more clearly in side elevation the flexible stick feeding rod guide means together with the supply hopper for the sticks.

Figure 3 is a similar view looking in a direction toward the left and taken substantially upon the line 3—3 of Figure 1.

Figure 4 is an elevational view of one side of the machine for disclosing more clearly a form of hand operating mechanism together with means for uncoupling the wire winding mechanism in order that the wire carrying spool may be replenished from the wire reel by rotation of the master shaft which, during the main operation of the machine is adapted to be alternately rotated in opposite directions.

Figure 5 is an enlarged fragmentary detailed sectional view for clearly disclosing the driving mechanism for the wire wrapping and stick feeding construction.

Figure 6 is an enlarged fragmentary vertical sectional view through the stick discharge end of the flexible rod guide tube for more clearly disclosing the position of the stick and flower stem during the wire wrapping operation and for disclosing in side elevation the wire wrapping arm that is carried by the wire spool.

Figure 6^a is an enlarged fragmentary cross section of the outlet end of said section for clearly disclosing the means for retaining a reenforcing stick therein after the feed rod has started upon a return movement in said flexible rod guide tube section.

Figure 7 is a detailed elevational view of the outer side of the wire winding arm together with the wire end clamping member that is disposed upon the discharge end of the flexible rod guide tube.

Figure 8 is a top plan view of this mechanism.

Figure 9 is a fragmentary elevational view of the upper end of the guide tube upon which is disposed said wire end clamp that has been automatically opened and shown in a position to be automatically closed at the time the wire winding arm returns to its normal position, this clamp being adapted to retain the end of the wire that projects outwardly from the end of the winding arm in order that the wire may be held at this end during the upward movement of the arm while the same is revolving around the flower stem and stick.

Figure 10 is an elevational view showing the opposite side of the clamp per se.

Figure 11 is a perspective of the clamp block per se with which is pivotally associated an automatically actuated clamping jaw.

Figure 12 is a similar view of the clamping jaw per se.

Figure 13 is a view similar to Figure 8, but differs therefrom inasmuch as the wire clamp in this figure is shown in a position just prior to being opened whereas in Figure 8 the clamp is shown just prior to being closed.

Figure 14 is a fragmentary sectional view through the top wall of the machine casing through an opening in which is disposed a relatively short spirally slotted tube in vertical alignment with the stick discharge end of the flexible rod guide tube for supporting a flower stem and reenforcing stick in a vertical manner and in close relation during the wrapping of the wire therearound. This view also discloses the automatically actuated wire cutter that is controlled at the time the wire carrying and wrapping arm reaches its upward limit of movement so that the wire that has been wrapped around the stem and stick may be severed from a wire supply upon the heretofore mentioned spool.

Figure 15 is an enlarged elevational view disclosing the means for automatically actuating the wire cutter.

Figure 16 is an enlarged fragmentary view taken substantially upon the line 16—16 of Figure 1 and looking in a direction toward the right for more clearly disclosing automatic mechanism for gradually forcing the wire carrying spool and the wire wrapping arm upwardly upon its guide shaft during the operation of the machine.

Figure 17 is an enlarged fragmentary sectional view through the stick supply hopper from which is automatically fed during each operation of the machine a single stick into the flexible rod guide tube in order that the same may be forced by the action of the flexible rod to a point partially outwardly of the discharge end of said guide tube, this view

disclosing the single stick lifting plunger in position primary to the injection of the stick into the guide tube which passes through the upper end of the hopper.

Figure 18 is a similar fragmentary view disclosing the single stick as having been fed into the tube after the flexible rod has been extended to a position within the tube to enable the ejection of the stick thereinto.

Figure 19 is a fragmentary vertical sectional view taken substantially upon the line 19—19 of Figure 17 for disclosing the relative position of the stick with respect to the flexible feed rod prior to the projection of the stick into the feed rod guide tube.

Figure 20 is a fragmentary bottom plan view of the main mechanism supporting frame disposed within the casing for more clearly disclosing a releasable latch mechanism that maintains the section of the flexible rod guide tube shown in Figure 6 within its supporting structure in an anti-vibration manner.

Figure 21 is a fragmentary elevational view partly in cross section disclosing the driving mechanism of the machine in such relation as to enable the master shaft to be continuously rotated in order that the wire spool may be rotated without its consequent vertical rising so that the wire from the main wire reel within the machine may be wound thereon for use in subsequent operations of the machine.

Figure 22 is an enlarged detail vertical section taken substantially upon the line 22—22 of Figure 21 for disclosing in side elevation the automatic means for slowly raising the wire carrying spool during the operation of the machine, in this instance the relationship of the parts being such as to prevent the raising of the spool at the time the wire is being wound thereon.

Figure 23 is a view partially in plan, and partially in section disclosing means controlled by the gear shifting mechanism in order that the parts of the machine may be properly related with respect to each other at the time of shifting the gears for obviously preventing the untiming of the parts when connecting or disconnecting certain gears when throwing the machine into position for the stem winding operation or the spool replenishing operation.

Figure 24 is a fragmentary vertical sectional view showing this construction in side elevation.

Figure 25 is an enlarged fragmentary view partly in elevation and partly in cross section disclosing the connecting means between the beforementioned flexible rod and its actuating arm.

Figure 26 is a view partly in elevation and partly in section disclosing the opposite end of the flexible rod from that shown in Figure 25, this end of the flexible rod car-

trying a cup within which is to be positioned one end of the reenforcing stick in order that the same may be positively moved to flower stem engaging position, and

5 Figure 27 is an elevational view of a flower disclosing the stem reenforced and wrapped in accordance with this invention.

Now having particular reference to the drawings, my novel machine constitutes the 10 provision of a suitable form of casing 5 that includes corner frame bars 6 preferably of angle iron construction that are interconnected by upper and lower cross bars 7. The front and rear walls of this casing are 15 preferably in the form of hinged doors 8 that may be secured in closed position through the medium of suitable latches 9. Pendent from the opposite side walls of the casing are boards 10 that afford supporting 20 feet for the machine, these boards being interconnected by a cross angle bar 11.

Within the casing directly above the lowermost frame connecting bars 7 is a horizontally disposed supporting structure that 25 includes a pair of spaced horizontal angle bars 12-12 that are connected at their opposite ends to transverse bars 13 that are secured at their respective ends to the corner posts 6 of the casing frame construction.

30 Rigidly secured to the spaced angle bars 12-12 adjacent the right hand end thereof is the base plate 14 of a gear casing 15 disposed within which is a relatively large spiral gear 16 slidably keyed as at 17 to a 35 horizontal shaft 18 that is journaled in bearings formed integral with the side walls of the gear casing and that extends at one end outwardly of the casing through an opening 19 in the adjacent side wall thereof, Figures 40 5 and 21.

Having mesh with said spiral gear 16 is a spiral pinion 20 that is carried by a shaft 21 journaled in horizontal alignment with the first mentioned shaft 18 within a bearing 45 unit that forms an integral part of the gear casing 15, Figures 1, 5 and 21. Upon the left hand end of this shaft 21 which as shown in these before mentioned figures is in vertical alignment with the shaft 18, is a relatively large bevel gear 22 for a purpose 50 hereinafter more fully described.

A further horizontal shaft 23 is journaled within the bearing unit formed at the top of the gear casing 15, the opposite ends thereof extending outwardly of the unit and having keyed to its left hand end a circular disk 24 and at its right hand end a relatively small and wide spur gear 25. Also keyed to this shaft 23 intermediate the spur gear 25 and the bearings is a relatively small flanged pulley 26 for a purpose hereinafter more fully described.

The spur gear 25 upon one end of said shaft 23 is normally in mesh with a relatively larger spur gear 27 that is keyed to

the first mentioned horizontal shaft 18 intermediate the gear casing 15 and adjacent wall of the machine casing 5 whereby when the shaft 18 is rotated in opposite directions in a manner and for the purpose hereinafter described alternate rotary movement will be imparted to the shafts 21 and 23.

Rigidly secured to the spaced parallel bars 12-12 of the before mentioned supporting frame is the base plate 28 of a vertically extending relatively elongated guide tube 29 within the upper end of which is a tubular bearing 30 that is shouldered at 31 for rest upon the upper end of the guide tube for obviously preventing the downward movement of the bearing therein. Directly above the upper end of said guide tube the bearing 30 is formed with a beveled gear 32 that has mesh with the relatively large bevel gear 22 upon the adjacent end of the second mentioned horizontal shaft 21. Extending upwardly from the bevel gear 32 and formed integral therewith is a combined drive and guide rod 33 for a wire carrying spool 34. This rod is relatively square shaped in cross section and is formed throughout its length with a vertical bore in communication with the tubular bearing 30 for the bevel gear 32, Figure 6.

The construction of the wire spool 34 employed in connection with a machine of this character is preferably as shown in said Figure 6, the same including heads 35 and 36 slightly beyond the opposite ends of the wire carrying member of said spool construction. The heads are formed with aligned central square shaped openings through which the rod 33 extends obviously facilitating the rotation of the spool during the rotation of the rod and the vertical sliding movement of the spool in opposite directions upon said rod.

The wire carrying portion per se of the spool construction is disposed over and has frictional engagement with a tube 37 that affords an interconnection between the heads 35 and 36. This detail of construction permits the unwrapping of the wire A from its carrying element per se during the rotation and vertical sliding movement of the spool construction.

Rigidly disposed within the guide tube 29, beveled gear bearing 30 and rod 33 is one section 38 of the stick feeding flexible rod guide tube 39, Figures 5 and 6. The upper end of this section of the guide tube extends slightly above the square rod 33 and secured thereon is a wire clamp 40 hereinafter more fully described. This section of the guide tube is maintained in a relatively rigid position within the guide 29, etc. through the provision of a releasable latch construction 41, Figure 20, that includes a latch plate 42 that is pivoted at one end as at 43 to one of the spaced parallel bars 12 of the supporting frame within the machine casing, the oppo-

site end of which is formed with an actuating finger piece 44. Adjacent this edge of the latch plate the same is notched as at 45 which receives the shank of a set screw 46 when the plate is closed, said set screw being received within a threaded opening of the opposite bar 12 of the said supporting frame. Intermediate the ends of this latch plate 42 the same is formed upon the inner edge thereof with a notch 47 that engages within the groove of a collar 48 that is rigidly secured to the section 38 of said flexible shaft guide tube 39, Figure 5. By releasing the latch mechanism and by removing the wire clamp 40 from the upper end of said flexible rod guide tube, this section thereof may be removed for repair or cleaning purposes. The lower end of this section 38 of said guide tube 39 terminates in a curved portion 49, Figure 1, that is to be placed in communication with the adjacent end of the intermediate section 50 which is disposed in a relatively horizontal manner, Figures 17 and 18, for a purpose hereinafter described, the opposite end of this intermediate section being also adapted to be placed in communication with the adjacent end of the other section 51 of said guide tube. This last mentioned section of the guide tube extends upwardly and is then bent into ring-like formation 52 which portion thereof is disposed in spaced relation with the adjacent side wall of the machine casing through the medium of hanger members 53, Figures 1, 2 and 21. Secured to or formed integral with the uppermost horizontal shaft 23 intermediate the spur gear 25 and pulley 26 is a right angularly extending arm 54, Figures 2 and 25, to the outer end of which is secured one end of the reenforcing stick feeding rod 55. This feeding rod 55 is necessarily of flexible formation being preferably in the nature of a coiled spring. The outer end of the arm 54 extends into the rod guide tube 39 through a slot 56 formed in this section of said tube. One end of the spring forming said flexible rod is brought outwardly of the tube through said slot 56 and is secured to the arm through the medium of a suitable clamp 57.

In so far as I have described my invention, it will be apparent that when the machine is set for flower stem reenforcing operation, the flexible rod 55 will be forced through the sections of the tube for feeding a single reenforcing stick B to the position shown in Figure 6 in a manner and for a purpose hereinafter to be more fully described.

The receptacle for the reenforcing stick consists of a relatively V-shaped hopper 58, the bottom wall of which is provided with a transverse slot through which is slidable a plate-like plunger 59 that is longitudinally grooved at its upper edge as shown in Fig-

ures 17 and 18. The intermediate section 50 of the guide tube 39 extends transversely of the upper end of the hopper, the opposite ends of the same being positioned within openings in the side walls thereof. The lower surface of this guide tube section 50 is provided with a slot through which the upper grooved end of the plunger is adapted to extend, Figure 18 for positioning a single stick therein during each operation of the plunger.

The free end of the flexible rod 55 carries a socketed member 60 for receiving the adjacent end of the stick B that is carried upwardly by the plunger 59 in order that when this rod is moved in the direction of the arrow, Figure 18, said stick will be positively moved within the tube 39 to the position shown in Figure 6.

In order that each stick B will be positively maintained in the position shown in said figure the upper end of the section 38 of said tube 39 is formed with a spring finger 61, Figure 6, that is struck out from the material forming this section of the tube. The upper end of the finger is bent inwardly of the tube and binds the stick against the wall of the tube for holding the same in such a position during the reversal of movement of the flexible rod.

In order that the sticks B will be positively engaged within the socket member 60 of the flexible rod there is provided a spring finger 62 that is connected at one end as at 63 to one wall of the hopper 58, the other end of this spring finger projecting into the section 50 of the tube through a slot 64 in the top surface thereof. It is apparent that this end of the spring finger always engages the sticks as they are moved upwardly into the tube through the action of the plate like plunger 59.

The operation of the plunger is controlled simultaneously with the alternate rotation of the uppermost horizontal shaft 23 and this operation is occasioned through the medium of a flexible spring strip 65 that is connected at one end to the before mentioned pulley 26 and at its opposite end to a retractile coil spring 66 that is in turn connected at its opposite end to the upper end of one of a pair of vertically extending tubes 67-67 that are secured to the lower end of the plunger and that are guided in their vertical sliding movement within bearings 68 suitably secured to the side walls of the hopper 58.

It will thus be seen that the rotation of the shaft 23 in one direction will occasion the winding of the band 65 upon the pulley 26 which will consequently raise the plunger 59 to the position shown in Figure 17. As will be presently more fully brought out the plunger moves upwardly simultaneously with the movement of the flexible rod in the

direction of the arrow in Figure 17. Obviously the stick that is carried by the plunger strikes the flexible rod but due to the provision of the retractile spring 66 sufficient play is allowed in the sliding movement of the plunger to facilitate the movement of the flexible rod in the direction of said arrow in said Figure 17. Immediately upon the flexible rod reaching the position shown in Figure 18 said spring 66 will further draw the plunger 59 upwardly for disposing the stick in position within the section 50 of the guide tube 39 in order that when the flexible rod starts to move in the direction of the arrow in Figure 18 the stick will be forced through the tube into the position shown in Figure 6.

In order that the plunger 59 may be moved rearwardly to stick obtaining position when the rotation of the shaft 23 is reversed there is provided a retractile coil spring 69 appropriately anchored at its opposite ends to the machine casing and one of the guide tubes 67 carried by said plunger.

Secured to the upper head 35 of the spool construction is a disc 70 that is formed at its edge with a vertically extending arm 71 that terminates at its upper end in an arcuate shaped wire guide tube 72. This arm 71 is formed upon its outer side with a pendent curved arm extension 73 that carries at its lower end a suitable wire guide pulley 74 over which the wire supply from the pulley construction is trained as indicated in Figure 6. This wire is then brought upwardly and passed through a suitable guide 75 after which it is trained outwardly through the guide 72.

Now returning to the wire clamp 40 that is rigidly secured to the upper projecting end of the section 38 of the rod guide tube 38 and referring particularly to Figures 9, 10, 11 and 12 inclusive, it will be noted that this clamp includes a head 76 formed with a central opening 77 for the reception of said projecting end of the tube section and being secured to this projecting end in any manner desirable preferably through the medium of the set screw shown in Figure 6. At one side of this head 76 there is formed a bore 78 within which is loosely disposed a pintle 79 that carries at one end a wire clamping jaw 80 that is of arcuate formation and so arranged with respect to the pintle as to position over an arcuate inclined portion 81 upon the top surface of the head when these parts are assembled. Pendent from one end of this jaw 80 is a leg 82 that is formed at the lower end thereof with a right angular lug 83. As the wire end carrying arm 71 reaches its lowermost limit of movement as shown in Figure 1, this lug 83 is engaged by a lug 84 upon the inner side of the arm 71 adjacent its upper end

for obviously moving the clamping jaw 80 to closed position in engagement with the surface 81 of the clamp head 76 in a manner as more clearly brought out by the arrows in Figure 9. This action will consequently 70 clamp the projecting end of the wire strand that engages outwardly of the guide tube 72 between the head and clamping jaw for holding the same during the reverse rotation of the wire carrying arm in its upward 75 movement as will be hereinafter more fully described.

The under surface of the clamping jaw 80 is preferably milled as at 85 for affording a positive clamping of the wire between the 80 jaw and head.

For limiting the upward movement of the spool construction at the wire end carrying arm the before mentioned disc 70 is provided upon its top surface with a lug 86 85 that strikes the lug 83 of the clamping jaw leg for obviously moving the clamping jaw to the open position as in Figure 13. The opening of the jaw will release the end of the wire for permitting the extraction of 90 the stem reenforced flower, hereinafter more fully described.

In order that the clamping jaw 80 may be maintained in open or closed positions until positively moved from closed to open position, and vice versa, there is provided upon the opposite end of the clamping jaw carrying pintle 79 a spring finger 87 that has frictional engagement with a pin 87 carried by the clamp head 76, Figures 10 and 11. 100

Disposed within an opening in the top wall of the machine casing is one end of a flower stem and stick guide tube 88 that is in vertical alignment with the flexible rod guide tube section 38, Figure 6. This tube 88 is spirally slotted at its lower end as at 89 to permit the wire A to be spirally wrapped around the stick B and stem C of the flower D during the operation of the machine. 110

For controlling the upward sliding movement of the spool construction and the wire end guide arm 71 during the rotation thereof the lowermost head 36 of the spool construction is circumferentially channelled as 115 at 90, Figure 6. Disposed within this channel 90 is the yoked end 91 of a rearwardly extending link 92, Figure 3, that is carried upon the upper end of a vertical rod 91' that is preferably square shape, the same being guided for vertical sliding movement within bearing blocks 92 formed upon the rear surface of the relatively elongated guide member 29. Intermediate these guide bearings 92 there is rigidly connected to this rod an arm 93 that has pivotal connection at its outer end to one end of a link 94. The lower end of this link 94 is in turn pivotally connected to an inwardly directed arm 95 that is mounted at its inner end for swing- 130

ing movement upon a pin 96 that is formed upon or otherwise secured to the aforementioned guide 29. Also mounted for swinging movement upon this pin 96 and operationally connected to said arm 95 is a bell crank shaped arm 97 that carries at its upper end a roller 98.

Keyed to the inner end of the first mentioned horizontal shaft 18 is a cam disc 99 necessarily of the shape shown in Figures 3 and 16 in order that when the machine is set for flower stem reenforcing operation the cam will, during the rotation of the shaft 18 in opposite directions so actuate the bell crank 97, arm 95, link 94, arm 93, rod 91 and link 92 to move the spool construction and wire end guide arm 71 in opposite vertical directions simultaneously with the rotation of the spool construction and wire end guide arm.

Formed upon the outer side of the cam disc 99 is a circular disc 100 of a radius slightly greater than the radius of the low point of the cam disc 99 in order that when the horizontal shaft 18 is shifted for cutting out the vertical movement of the spool construction, the spool construction will be held at such a position as to prevent the engagement of the wire end guide arm carrying lug 84 with the lug 83 of the clamp jaw arm 82.

Now describing the operation of the machine in so far as the description thereof has progressed I will assume that a reenforcing stick has been automatically moved to the position shown in Figure 6 and held in such a position through the medium of the spring finger 61 of the flexible rod guide tube section 38 and that a flower has been inserted in the spirally slotted tube 88 and supported in such a position in close relationship with the stick B by resting upon the inwardly bent end of said spring finger 61 as in Figure 6^a. I will assume that the end of the wire projecting inwardly from the guide tube 72 of the arm 71 has been secured within the clamp construction 40. A rotation of the master shaft 18 in a manner hereinafter described in one direction will obviously through the medium of the gearing construction cause a rotation of the square rod 33, and a simultaneous rotation of the wire spool construction and wire end guide arm 71. Immediately upon the spool construction rotating, the wire will begin wrapping around the stem and stick in a manner as shown in Figure 6. In order that the wire may be drawn from its carrying element of the spool construction and in order that the spiral wrapping of the wire may be occasioned, the spool construction is slowly moved upwardly upon the rod 33 through the medium of the cam and lever construction hereinbefore described. As soon as the wire reaches the lowermost end of the tube 88, the same will pass into the open

end of the spiral slot 89 of said tube for manifestly occasioning a drawing of the wire from its carrying member and the same will also act upon the wire so as to form the spiral wrapping of the same 70 around the stem and stick.

Immediately upon the spool construction of the wire end guide arm reaching the upward limit of movement the wire between the spirally slotted tube and guide 72 will 75 pass between the stationary and movable blade 101 and 102 respectively of a wire cutter whereupon the movable blade will be automatically actuated to closed position for cutting the wire. Simultaneously with this 80 operation, the lug 86 of the guide wire arm carrying disc 70 will strike the lug 83 of the clamping jaw arm 82 for releasing the lowermost end of the wire that has been wrapped around the stem in order that the 85 stem in a reenforced and wire wrapped condition may be removed from the tube 88 and the same will appear identical with the showing in Figure 27.

The actuating mechanism for the movable blade 102 of the wire cutter constitutes the provision of a pendent arm 103 that is pivotally connected to the outer end of the movable blade 102 and carries at its lower end a plate 104 that is provided with a vertical slot 105 within which engages the shank of a set screw 106 that is disposed within a central screw threaded opening of the disc 24 that is carried upon the end of the uppermost horizontal shaft 23. This plate 104 is provided with a shoulder 107 that is engaged by a set screw 108 carried by said disc 24 in order that as the disc moves in the direction of the arrows shown in Figure 15, the member 103 will be raised upwardly for obviously closing the blade 102 which will thereupon snip the wire after the same has been wrapped around the flower stem and stick.

Upon rotation of the master shaft 18 in an opposite direction the set screw 108 of disc 24 will engage the curved edge 109 of the plate 104 upon the end of the member 103 for drawing said member 103 downwardly for opening the movable blade of the cutter, the slot 105 in said plate permitting of this movement of the member 103.

Simultaneously with the upward movement of the spool construction upon the rod 33 the flexible rod 55 moves rearwardly within the guide tube 39 and after the socket carrying end thereof has reached the position shown in Figure 18 the feed plunger 59 within the hopper 54 will move to the position shown in Figure 18 in order that as the spool construction is being returned downwardly, a single stick is being moved into the position shown in Figure 6. The operation of the feed plunger and flexible

rod are so timed with respect to each other that the feed plunger 59 begins moving upwardly simultaneously with the rearward travel of the rod.

- 5 Immediately upon the spool construction reaching its lowermost limit of movement the projecting end of the wire from the guide tube 72 will engage between the head 76 and clamping jaw 80 of the clamping construction 40 whereupon the lug 84 of the wire end guide arm 71 will strike the lug 83 of the clamping jaw leg for again securing the end of the wire in position for allowing a subsequent operation of the device.
- 10 In this connection I wish it to be understood that it is necessary to first rotate the master shaft 18 a full turn in one direction which will occasion the wrapping of the wire upon the flower stem and stick and a rotation of 15 the master shaft in an opposite direction returns the parts to initial position.

Any desirable means may be employed for alternately rotating the master shaft 18, but for the purpose of illustration I have 20 disclosed the end of this shaft that projects through the openings 19 of the machine casing as equipped with a handle lever 110.

In order that the master shaft 18 may be moved horizontally within its bearings for 25 disengaging the primary drive gear 27 from the gear 25 of the shaft 23 in order that the master shaft 18 may be rotated for imparting a continuous rotation to the spool construction 34 for a purpose hereinafter to be 30 more fully described, said shaft 18 is formed directly inwardly of the handle 18 with a grooved collar 111. Engaging within the groove of this collar are inwardly directed pins or lugs carried upon the opposite arms 35 of a fork shaped plate 112 which is rigidly connected to a shaft 113 journaled within suitable bearings 114 positioned upon the adjacent side wall of the machine casing, Figure 4. This shaft 113 carries a short inwardly extending arm 115 to which is universally pivotally secured the lower end of a length adjustable rod 116, the upper end 40 of which is eccentrically connected at 117 to one end of a horizontal shaft 118 that is 45 journaled at its opposite end with the bearing 119 also carried by the adjacent side wall of the machine casing. This shaft 118 carries a handle lever 120 and it will be obvious that by throwing the same downwardly into the position shown in Figure 1 the 50 shaft 113 will be so rotated as to slide the shaft 118 outwardly into the position shown in said figure for obviously disengaging the gears 27 and 25.

55 In order that the gear 27 may disengaged from the gear 25 and reengage therewith without the consequent untiming of the different units of construction, there is pivotally arranged upon this side wall of the machine casing a forked plate 121 that is nor-

mally forced downwardly in the direction of the arrow in Figure 24 through the medium of a spring 122. The downward movement of this forked plate is limited through the presence of a pin 123 that will engage 70 the wall of the casing after the same has been moved to a substantially horizontal position. In order that the gears 27 and 25 may be connected or disconnected without placing the units of construction in 75 untimed relation, the handle lever 110 is brought into the position shown in Figure 4 after which the lever 121 is swung downwardly as in Figure 21 at which time the fork plate will engage the handle lever 110 80 and prevent any accidental movement of the same during the unmeshing actuation of said gears. It will thus be seen that after the shaft 18 has been moved to the position shown in Figure 21 the same may be continuously rotated for imparting a continuous rotation to the wire spool construction.

When the gears are again to be brought into intermeshing relation, the handle 110 is brought to a position directly adjacent 90 the forked plate 121 after which the lever 120 is turned to the position shown in Figure 4 and there maintained by a suitable latch plate 124.

In order that the spool construction 34 95 may be replenished there is suitably supported for rotation within the machine casing a wire reel 125 and obviously whenever it is desired to replenish the supply of wire upon the spool construction, one end 100 of the supply upon the reel 125 is suitably secured to the wire carrying member of the spool construction after which the handle lever 110 is rotated continuously which will 105 through the medium of the shaft 18 impart rotation to the rod 33 through the medium of the gearing connection comprising the large bevel gear 22 and small bevel gear 32 rotate the spool construction 110 for winding the wire thereon.

An additional feature of my invention is to provide means for preventing the undue rotation of the wire carrying member of the spool construction upon the tube 37 during the stem winding operation, this means comprising a spring plate 126 that is carried by the under side of an extension 127 formed upon the disc 70, the outer free end of which is adapted to adjustably frictionally engage the upper end of the wire carrying member of the spool construction in a manner as clearly shown in Figures 6 and 8. Further details of operation will be apparent to those skilled in the art, and I wish to be herewith understood that I do not wish 120 to be limited to the specific structural elements shown and described insomuch as all the same may be improved or modified without departing from the spirit or scope of the appended claims.

Having thus described the invention, what I claim as new is:—

1. In a machine of the class described, a holder for a stem, means for delivering to and supporting in said holder a stick, means for wrapping wire around the stick and stem in the holder, and means for severing the wire when a predetermined amount thereof has been wrapped around said stick and stem in the holder.
2. In a machine of the class described, a stem holder, a source of supply of suitable length sticks, means for singly feeding said sticks to position in parallel relation with a stem in the holder, and means for wrapping wire around the stem and stick in the holder.
3. In a machine of the character described, a stem holder, a source of supply of suitable length sticks, means for singly feeding said sticks to positions in parallel relation with a stem in the holder, means for wrapping wire around a stem and stick in the holder, and means for severing the wire after a predetermined amount thereof has been wrapped around said stick and said stem in the holder.
4. In a machine of the class described, a stem holder, a source of supply of suitable length sticks, means for singly feeding said sticks to position in parallel relation with a stem in the holder, a source of wire, means for holding an end of said wire, and means for moving the source of wire about a stem and stick in the holder to wrap the wire thereabout.
5. In a machine of the class described, a stem holder, a source of supply of suitable length sticks, means for singly feeding said sticks to position in parallel relation with a stem in the holder, a source of wire, means for holding an end of said wire, means for moving the source of wire about a stem and stick in the holder to wrap the wire thereabout, and means for severing the wire after a predetermined length thereof has been wrapped about the stick and the stem in the holder.
6. In a machine of the class described, a stem holder, a stem holder, a source of supply of suitable length sticks, means for singly feeding said sticks to position in parallel relation with a stem in the holder, a source of wire, means for holding an end of said wire, means for moving the source of wire about a stem and stick in the holder to wrap the wire thereabout, means for severing the wire after a predetermined length thereof has been wrapped about the stick and the stem in said holder, said means for holding the end of the wire adapted to release and obtain a new grip on a new end of the wire of said source.
7. In a machine of the class described, a stem holder, a source of supply of suitable length sticks, means for singly feeding said sticks to position in parallel relation with a stem in the holder, and means for automatically spirally wrapping a predetermined length of the wire around a positioned stem and stick in the holder.
8. In a machine of the class described, means for retaining a stem and a stick in parallel relation, mechanical means for wrapping a predetermined length of material around the stem and stick, and automatic means for severing predetermined lengths from a supply of said material at the end of the wrapping operation.
9. In a machine of the class described, means for retaining a stem and a stick in parallel relation, mechanical means for wrapping a predetermined length of material around the stem and stick, automatic means for severing predetermined lengths from a supply of said material at the end of the wrapping operation, and means for delivering sticks singularly to the first mentioned means so that by placing the stems in engagement with said first mentioned means the operation can be continuously carried on.
10. In a machine of the class described, a holder, means for supporting a stick in parallel relation with a stem in the holder, a wire spool construction mounted for rotation, means for drawing the wire from the spool and simultaneously wrapping the same around the stick and stem, and means for moving the wire spool in a direction toward the stem and stick to occasion the spiral wrapping of the wire.
11. In a machine of the class described, a supporting member for holding a pair of elements temporarily together, a wire spool construction mounted for rotation, means for drawing the wire from the spool and simultaneously wrapping the same around the elements, and means for moving the wire spool in a direction toward said elements to occasion the spiral wrapping of the wire around the elements.
12. In a machine of the character described, a holder, means for supplying singly and supporting a stick in parallel relation with a stem in the holder, a wire spool construction mounted for rotation, means for drawing the wire from the spool and simultaneously wrapping the same around a stick and stem in the holder, and means for moving the wire spool in a direction toward said holder to occasion the spiral wrapping of the wire.
13. In a machine of the class described, a holder for a stem, a stem reinforcing stick supply container, automatic means for positioning a single stick from the container in parallel relation with a stem in the holder,

and automatic means for applying an interconnecting member to a stem and stick in the holder.

14. In a machine of the class described, a holder for a stem, a stem reenforcing stick supply container, automatic means for positioning a single stick from the container in parallel relation with a stem in the holder, and automatic means for interconnecting a stem and stick while in the holder comprising a source of wire supply, means for wrapping a predetermined length of the wire around the stem and stick in the holder, and means for severing the predetermined length of the wire from the source of supply thereof at the end of the wrapping operation.

15. In a machine of the character described, a holder for a stem, a source of re-enforcing stem sticks, means for disposing a single stick into close relation with a stem in the holder, a source of flexible binding material, and means for wrapping a predetermined length of the binding material around a stick and stem.

16. In a machine of the character described, a holder for a stem, a source of flexible wire, means for delivering singly sticks to the holder, automatic means for clamping the free end of the wire to a point adjacent a stem and stick in the holder, means for wrapping the wire around the stem and stick in the holder, and means for releasing said clamp during the wrapping operation.

17. In a machine of the class described, a holder for a stem and a reenforcing stick, a source of flexible wire, means for clamping the free end of the wire from the source to a point adjacent a stem and stick in the holder, automatic means for spirally wrapping a predetermined length of the wire around the stem and stick in the holder, means operable automatically during the wrapping operation for releasing said clamp, and automatic means for severing the predetermined length of wire from the source thereof at the end of the wrapping operation.

18. In a machine of the class described, a holder for a stem and stick in parallel rela-

tion, a source of flexible wire, means for clamping the free end of the wire from the source thereof to a point adjacent a stem and stick in the holder, automatic means for spirally wrapping a predetermined length of the wire around the stem and stick in the holder, means operable automatically during the wrapping operation for releasing said clamp, and automatic means for severing the predetermined length of the wire from the source thereof at the end of the wrapping operation comprising a cutter blade mounted for operation adjacent one end of the holder.

19. In a machine of the class described, a holder for a stem, a hopper for receiving a supply of suitable length sticks that are to be directed into the holder in parallel relation with a stem therein, automatic means for moving a single stick into position adjacent a stem within the holder, a source of wire, and automatic means for wrapping the wire about a stem and stick in the holder.

20. In a machine of the class described, a holder for a stem, a source of supply of suitable length reenforcing sticks, automatic means for moving the sticks singly into position parallel with a stem in the holder at each complete operation of the machine, and automatic means for uniting a stick and stem in the holder.

21. In a machine of the class described, a holder for a stem, and a stick in parallel relation, a spool mounted for rotation and for movement toward and away from the stem and stick in the holder, means for automatically rotating and otherwise moving the spool during the operation of the machine, means for spirally wrapping the wire from the spool around the stem and stick, a wire supply reel, and means for cutting out the movement of the spool toward and away from the stem and stick in the holder in order that a further supply of wire from the wire supply reel may be wound upon the spool during the rotation of the same.

In testimony whereof I affix my signature.

ELMO L. BROWN.
